UNITED STATES PATENT OFFICE.

WILLIAM BISSET, OF PENARTH, ENGLAND.

APPLIANCE FOR LOADING SHIPS WITH COAL OR THE LIKE.

No. 857,784.

Specification of Letters Patent.

Patented June 25, 1907.

Application filed August 12, 1905. Serial No. 273,961.

To all whom it may concern:

Be it known that I, WILLIAM BISSET, a subject of the King of Great Britain and Ireland, and a resident of 5 Herbert Terrace, 5 Penarth, county of Glamorgan, Great Britain, have invented certain new and useful improvements in appliances for loading ships with coal and other similar substances or merchandise consisting of a distributing-
10 box forming a suspended cone, of which the following is a specification.

This invention relates to an appliance for loading ships with coal and other similar substances or merchandise and which by the addition of extra slides as set forth enables the coal to run down to the bottom of the ship's hold, and in order that my said invention may be readily understood reference is to be had to the following description and accompanying sheets of drawings in which:—

Figure 1 represents a half elevation of the apparatus constructed in accordance with my said invention. Fig. 1^a a half sectional elevation; and, Fig. 2 a side elevation thereof.

Like letters of reference indicate corresponding parts in the said figures.

In carrying my said invention into effect I form the distributing and loading box *a* of metal, rectangular in shape (preferably square) and of a depth greater than the width of said box and suspend the same from the crane hook by means of the chains *b* connected to the corners of the flared mouth *c* of said box.

In the sides *d* of the box *a* I arrange an opening *e* partially closed by the doors *f* suspended on hinges *g* so as to open automatically under pressure from within.

At a suitable height from the top of the box and parallel with the openings thereof I arrange a plate *h* (see Fig 1^a) extending across said box and on either side of said plate I attach the chutes *i* arranged at a fixed and suitable angle, for instance 45° passing underneath the doors *f* thus forming a suspended cone. These chutes I also connect with the box *a* by means of the plates *j* which serve the purpose of guiding the coal on to the slides *l* connected with the chutes *i* by means 50 of the hinges *m* or equivalent devices. These slides *l* I provide at their lower ends with

hooks *n* adapted when required to engage with eyes or slots *o* carried on the upper ends of the additional slides *p* when running the coal down to the bottom of the ship's hold. 55

To vary the angle of the slides the same are provided with brackets *q* to which are attached cords, chains or the like *r* fastened at their outer ends to the combings of the ship's hatchways, or in any suitable place, 60 the angle of the cords chains or the like being according to circumstances.

It is to be noted that the box or receptacle *A*, is provided with the reinforces or braces *A'* which terminate above the box 65 and are provided with eyes to allow the chains *B* to be connected thereto.

It will be observed that there is also an opening below the lower edge of the gate *f*, for a moderate or light discharge of coal and 70 that the side walls of the chute are so high above the said lower edge of the gate, that in the case of a heavy discharge and the consequent outward swing of the gate between the said sides, the lower edge thereof will 75 not be swung above the upper edges of said sides, whereby the gate operates as a guard to prevent coal during a heavy discharge from spilling over the sides of the chute.

Although I have only shown two additional slides yet I wish it to be understood that I do not limit myself to such as I may attach more or less according as circumstances dictate. 80

In use the charge of coal entering the box 85 *a* is broken and diverted in both directions by means of the plate *h*, the coal passing through the openings left by the doors but should there be any tendency to choke the doors *f* automatically yield under the pressure 90 within thereby giving increased opening for the passage of the coal to the chute and slides *l* and *p* down which it is guided by the walls *s* thereof.

In some cases I find it advantageous to 95 secure the doors *f*. This I effect by any suitable arrangement of cross bars as at *t* (see Fig. 2).

What I claim and desire to secure by Letters Patent of the United States is:—

1. In a device of the character described, a receptacle, braces for the receptacle ex-

tending thereabove and terminating in eyes, supporting connections secured to the eyes and a chute depending from the receptacle.

2. An appliance for loading ships for coal or like material comprising an elevated bin with upright sides, a chute having an inclined bottom and upright sides arranged in connection with the upright sides of the bin, a gate pivoted to the upper portion of the bin side, and projecting down between

the sides of the chute but leaving a discharge space between it and the bottom of the chute.

In testimony whereof I have affixed my signature in presence of two witnesses.

WILLIAM BISSET.
